COMBINATION GARMENT DISPLAY ARM AND MOUNTING BRACKET

Stanley A. Friedberg, 7143 Woodrow Wilson Drive,
Hollywood, Calif. 90028

Filed Jan. 21, 1974, Ser. No. 435,304

Term of patent 14 years

Int. Cl. D20—03

U.S. Cl. D6—116

Fig. 1

Fig. 2

Fig. 3

Fig. 4

Fig. 5

Fig. 6

FIG. 1 is a perspective view of a combination garment display arm and mounting bracket showing my new design;

FIG. 2 is a side elevational view thereof;

FIG. 3 is a top plan view thereof;

FIG. 4 is an enlarged fragmentary side elevational view thereof;

FIG. 5 is an enlarged rear elevational view thereof; and

FIG. 6 is an enlarged fragmentary bottom plan view thereof.

I claim:

The ornamental design for a combination garment display arm and mounting bracket, substantially as shown.
